UNITED STATES PATENT OFFICE.

DENNIS B. D. BLAKE, OF QUINCY, ILLINOIS.

SHOCK ABSORBER.

Application filed July 22, 1922. Serial No. 576,733.

To all whom it may concern:

Be it known that I, DENNIS B. D. BLAKE, a citizen of the United States, and a resident of Quincy, in the county of Adams and State of Illinois, have invented a new and Improved Shock Absorber, of which the following is a full, clear, and exact description.

This invention relates to a shock absorber, and has particular reference to one which is an improvement over the shock absorber disclosed in my copending application, Serial No. 443606, filed February 9, 1921, entitled "Shock absorber."

15 An object of this invention is to provide means whereby quick and simple adjustment of the parts may be achieved.

Another object resides in the provision of means whereby the device can be efficiently and economically manufactured and assembled and disassembled.

A further object resides in the provision of means whereby the tension of the spring used can be quickly adjusted independently 25 of other adjustments.

A still further object resides in the particular construction and arrangement of parts which are hereinafter described and claimed and shown in the accompanying drawings.

30 The invention is illustrated in the drawings, of which—

Figure 1 is a vertical longitudinal section taken on the line 1—1 of Fig. 2.

Fig. 2 is a vertical transverse section taken 35 on the line 2—2 of Fig. 1.

Fig. 3 is a side elevation of the device.

Fig. 4 is a side elevation of the base plate.

Fig. 5 is a side elevation of the friction collar.

40 Fig. 6 is a section of the base plate taken on the line 6—6 of Fig. 4.

Fig. 7 is an end elevation of the adjustment sleeve.

The form of the invention shown in the 45 drawings is a preferred form, although it is understood that modifications in the construction and arrangements of the parts and in the character of the materials used may be adopted without departing from the 50 spirit of the invention.

The invention as shown in the drawings, which illustrates one preferred form the invention may assume, includes a base plate 1 having a flange 2 and rearwardly extend-

ing bosses 3 and 4 (see Fig. 6) in which are 55 disposed apertures 5 and 6. These bosses form pockets 7 and 8 in which may lie the heads of bolts, or nuts, adapted to fasten the base plate to any suitable portion of the frame of the automobile or other device on which 60 the absorber is mounted. The base plate is provided with a central hub 9 having a threaded aperture 10 therein to receive the threaded end 11 of a center bolt 12 having a head 13.

A consideration of the interior formation 65 of the base plate shown in Fig. 4 will disclose a plurality of lugs or projections 14 and 15 disposed along the inner wall of the base plate and preferably about 60° apart 70 in a line radial to the center of the base plate and on the opposite side therein from a recess 16. In this recess 16 a clamping plate 17 is disposed. This clamping plate is adapted to be adjusted by the engagement 75 therewith of a set screw 18 having a head 19 and adapted to be locked in position by a jam nut 20. The inner face 21 of this clamping plate is curved and adapted to bear against the curved edge of a friction collar 80 plate 22. The periphery of this plate is provided with a plurality of notches or indentations 23 shaped similarly to the lugs or projections 14 and 15 and spaced a corresponding distance apart around the periphery of 85 the friction collar plate. In these notches the lugs or projections 14 are adapted to lie in the manner shown in Fig. 1, and then by reason of the clamping engagement of the plate 17 the friction collar plate 22 can be 90 held in any desired position.

As shown in Fig. 5, this collar plate 22 is provided with an inwardly projecting curved flange portion 24 which extends around the inner face of the plate 22 adjacent its periphery a substantial distance. This flange, as shown in Fig. 1, is adapted to lie between layers of fabric or webbing such as 25 and to check the motion thereof due to the friction therebetween. It will 100 also be observed that the friction collar plate 22 is held in frictional engagement with the base plate 1 by reason of the action of the bolt 12. The collar plate is provided with a central aperture 25 somewhat larger than the diameter of the bolt 12. This aperture is surrounded by a hub 26 and this in turn is surrounded by a toothed ring 27 the teeth

of which are adapted to engage with similarly shaped teeth 28 on the inner end of an adjusting sleeve 29. This adjusting sleeve has its outer opposite end threaded as shown 8 at 30 and also has a hexagonal head 31. The bore 32 in the sleeve 29 is somewhat larger than the diameter of the bolt 12. A washer 33 is disposed between the head 31 of the sleeve 29 and the head 13 of the bolt 10 12. A lock nut 34, provided with an outwardly extending flange 35, is threaded on to the end of the adjusting sleeve 29, and a flange 34 bears against the edge of a central aperture in a cover portion 36 provided with 15 a flange portion 37 lying adjacent and against the flange 2 of the base plate. It will be apparent from a consideration of Figs. 1 and 2 that the tightening of the bolt 12 will cause the adjusting sleeve 29 to bear 20 against the collar plate 22, and this in turn will be forced against the inner face of the base plate 1. These elements are, therefore, held in firm and rigid relation. Moreover, the lock nut 34 bearing against the cover 36 25 will hold it firmly in place so that it will properly enclose the other elements.

In Fig. 7 I illustrate an opening 38 in the side wall of the adjusting sleeve 29. This is to permit the end 39 of a spring 40 to be bent 30 therearound and engage the adjusting sleeve. This spring 40 is then wrapped around the sleeve and the other end is bent around, as indicated at 41, through a slot 42 in a spring casing 43. This spring casing is made of any 35 suitable material and is substantially rigid as compared to the flexibility of the spring 40. This casing in reality confines the spring within a definite circumference but also serves as a firm support around which 40 to wrap the layers of fabric 25. At 44 is shown one end of the fabric fastened to the casting in any desired manner, the fabric being thereafter wound around the casting layer upon layer. 45 In practice, when an adjustment of the friction collar plate 22 alone is required, the jam nut 20 and the set screw 18 are unscrewed until the clamping plate 17 is free to move back into the recess 16, whereupon 50 by slightly releasing the center bolt 12 and applying a wrench to the hexagonal head 31 of the adjusting sleeve 29, the whole assembly of the spring 40, the webbing or fabric 25 and the collar plate 22 may be 55 rotated to any desired position until a desired notch 23 engages with the lugs or projections 14 and 15. This combined movement is possible because the teeth 28 of the adjusting sleeve and the corresponding teeth 27 on the collar plate 22 are held 60 in engagement by only partly unscrewing the center bolts. Furthermore, the aperture 25 and the aperture 32 are sufficiently larger than the diameter of the center bolt 12 to permit the necessary lateral movement 65

for rotating the friction collar plate 22 to engage the different notches with the lugs or projections 14 and 15.

If, however, only the tension of the spring 40 needs adjustment, the set screw 18, the jam nut 20 and the plate 17 should be locked rigidly and the center bolt 12 should be unscrewed until the teeth 28 on the adjusting sleeve 29 clear the corresponding teeth 27 on the collar plate 22. This permits the independent turning of the adjusting sleeve and the rotation of the same, the spring 40 being wound or unwound by reason of the engagement of one end of it with the adjusting sleeve in the manner above described. 80

Referring to Fig. 1, it will be observed that any downward pull on the free end of the webbing or fabric 25 will produce a corresponding movement in all the inside coils of webbing; and since the spring 40 folds around the adjusting sleeve 29, the necessary force to resist the spring action will be exerted through the spring casing 43, and a frictional resistance will also be exerted on the inside of the friction collar along that portion of it marked 45 in Fig. 1, as well as along the outside of the collar along that portion marked 46 in Fig. 1. 90

One of the important features of my invention resides in the coils of webbing and the spring bolt between the flange or collar 95 24 and the adjusting sleeve 29, thus allowing full and free action to the coil spring and providing inside as well as outside frictional resistance to rebound shocks. This folding spring action also makes possible the constant spreading position of the coils 100 of webbing, as shown at 47 in Fig. 1.

The spring casing 43 serves the double purpose of confining the coil spring 40 to a proper outside diameter, as well as providing the means of attaching the inner end of the webbing to the outer end of the spring. It also forms a drum on which the webbing is rewound on the recoil action of 105 the spring. It will also be noticed that the width of this spring casing 43 is not as great as that of the webbing 25, and since the webbing is attached to the casing 43, and since the outer end of the spring 40 is attached to 110 the casing 43 through the slot 42 previously referred to, and since the inner end of the spring is confined in the slot 38 of the adjusting sleeve 29, this construction prevents 115 a metal to metal contact of the moving parts and eliminates the necessity for lubrication, 120 making the action of the whole instrument exceedingly quiet.

With reference to the lock nut 34, this is 125 preferably made of bronze, and a slot is formed therein as indicated in Fig. 3 by the numeral 48. It will be seen that as the beveled surface 49 of this nut comes in contact with the opening in the cover 36, the slot 48 will be decreased in width as the 130

is pressed more firmly into position, and the elasticity of the metal of the nut will allow the threads to grip more tightly the threads of the adjusting sleeve and thus remain until such grip is forcibly removed.

What I claim is:

1. A shock absorber which includes a base plate having lugs thereon spaced apart, a friction collar disposed within said base plate, a collar plate on which said collar is mounted, said collar plate having notches in its periphery to engage with the lug, a clamping plate disposed within the base plate opposite the lug and adapted to engage the edge of the collar plate, and a set screw mounted on the base plate and engaging the clamping plate to adjust it against the edge of the collar plate.

2. A shock absorber which includes a base plate, a collar plate disposed against the inner face of the base plate, means for adjusting the angular position of the collar plate within the base plate, a friction collar mounted on said collar plate and extending therefrom in the form of a flange, teeth on the inner face of said collar plate, an adjusting sleeve, teeth on the inner end of said sleeve adapted to engage the teeth on the collar plate to lock the adjusting sleeve with respect to the collar plate, a coiled spring the inner end of which is attached to the adjusting sleeve, a circular spring casing enclosing said spring and to which the outer end of the spring is attached, a plurality of layers of webbing or fabric wound around the casing, the inner end of the fabric being connected to the casing, said friction collar being disposed between certain of the layers of said webbing along part of their length to produce friction therebetween when the webbing is moving, and a bolt extending between the outer end of the adjusting sleeve and the base plate to hold the base plate, the collar plate and the adjusting sleeve in an assembled relation.

3. A shock absorber which includes a base plate, a friction collar plate movably disposed therewithin, a friction collar extending from said plate, in the form of a flange, an adjusting sleeve, a coiled spring connected at one end to said sleeve, a spring casing enclosing said spring to which the outer end of the spring is connected, a plurality of layers of webbing wrapped around the casing, a portion of said webbing engaging with the friction collar, means for adjusting the angular position of the collar within the base plate, means for adjusting the angular position of the adjusting sleeve to determine the tension of the spring, and means for holding the base plate, the collar plate and the adjusting sleeve in an assembled relation.

4. A shock absorber which includes a base plate having a threaded aperture therein, a

bolt having a threaded end to extend into said aperture, a collar plate disposed against the inner face of the base plate, said collar plate having an aperture therein substantially larger than the diameter of said bolt, an adjusting sleeve surrounding the bolt and having an aperture therein substantially larger than the diameter of the bolt, and teeth on the inner face of the collar plate and the inner end of the sleeve adapted to engage to hold the sleeve and the collar plate in a determined angular position, said bolt having a head bearing against the outer ends of the sleeve whereby the bolt will hold the sleeve, the collar plate and the base plate in a definite position with respect to each other.

5. A shock absorber which includes a base plate having a threaded aperture therein, a bolt having a threaded end to extend into said aperture, a collar plate disposed against the inner face of the base plate, said collar plate having an aperture therein substantially larger than the diameter of said bolt, an adjusting sleeve surrounding the bolt and having an aperture therein substantially larger than the diameter of the bolt, and teeth on the inner face of the collar plate and the inner end of the sleeve adapted to engage to hold the sleeve and the collar plate in a determined angular position, said bolt having a head bearing against the outer ends of the sleeve whereby the bolt will hold the sleeve, the collar plate and the base plate in a definite position with respect to each other, said collar plate having notches on its periphery and projections on the base plate adapted to engage in said notches to determine the angular position of the collar plate with respect to the base plate.

6. A shock absorber which includes a base plate having a threaded aperture therein, a bolt having a threaded end to extend into said aperture, a collar plate disposed against the inner face of the base plate, said collar plate having an aperture therein substantially larger than the diameter of said bolt, an adjusting sleeve surrounding the bolt and having an aperture therein substantially larger than the diameter of the bolt, teeth on the inner face of the collar plate and the inner end of the sleeve adapted to engage to hold the sleeve and the collar plate in a determined angular position, said bolt having a head bearing against the outer ends of the sleeve whereby the bolt will hold the sleeve, the collar plate and the base plate in a definite position with respect to each other, said collar plate having notches on its periphery, projections on the base plate adapted to engage in said notches to determine the angular position of the collar plate with respect to the base plate, a clamping plate disposed against the edge of the collar plate opposite the projections on the base

plate, and means for pressing the clamping plate against the edge of the collar plate.

7. A shock absorber which includes a base plate having a peripheral flange, an adjusting sleeve having an outer threaded portion, a cuplike cover, the outer edges of which engage said flange on the base plate, said cover having a central aperture, a flanged lock nut having a threaded bore to engage

the threaded portion of the adjusting sleeve, 10 and a beveled surface to engage the edges of the aperture and cover, said lock-nut being split so that as the nut is threaded on the sleeve the engagement of the beveled surface with the edges of the aperture and the cover will force the split ends of the nut together to tighten it on the sleeve. M

DENNIS B. D. BLAKE.
